UNITED STATES PATENT OFFICE.

DELBERT HITCHCOCK, OF MILLERSBURG, OHIO.

ELECTRIC TIME SWITCH.

Application filed March 26, 1923. Serial No. 627,889.

To all whom it may concern:

Be it known that DELBERT HITCHCOCK, a citizen of the United States, residing at Millersburg, in the county of Holmes and

5 State of Ohio, has invented certain new and useful Improvements in Electric Time Switches, of which the following is a specification.

This invention relates to an electric time switch that is adapted to be placed over the face of an ordinary clock by mounting the device on the hour hand spindle of the clock.

The primary object of my invention is to provide an electric switch attachment to 15 clocks that can be so set as to make a contact at any given hour and also arrange that the contact can be broken later on at any given hour.

A further object of my invention is to 20 provide an electric time switch attachment for clocks, that is simple in operation and construction, durable, efficient for the purpose intended and one that can be manufactured and placed on the market at a 25 relatively low cost.

An electric time switch attachment for 30 clocks of this character is particularly adapted for use in the feeding of poultry, operating of lights in places where lights are not required during certain hours, and 35 also for the turning on and off of heat when buildings are heated at night.

These and like objects will be better understood as the description of my invention 40 proceeds and as is specifically pointed out in the appended claims.

Referring to the drawings which form a part of this specification,

Figure 1 is a plan view of an electric 45 time switch attachment for clocks constructed in accordance with my invention.

Figure 2 is a vertical section taken on line 2-2 of Fig. 1.

Referring to the drawings in detail, like 45 numerals will be used to designate like parts in the different views.

The numeral 1 denotes the face or dial of a clock, 2 the hour hand spindle on which my electric switch designated as a whole by 50 the numeral 3 is mounted. My switch attachment comprises a circular connecting lever ring 4, which is spaced apart from the face of the dial of the clock by insulators 5, which are fastened to the face of the 55 clock by any suitable means. A circular insulating ring 6 is placed within the

circular connecting ring 4. The insulating ring 6 is provided with twelve metal segments 7 which are secured thereto in any suitable manner. The metal segments 7 60 correspond to the hour marks on the dial of the clock. Pivotedly connected to the metal circular ring 4 as at 8 are twelve levers 9, which correspond to the number of metal segments and the hour marks on the dial of 65 the clock.

A dog disc 10 is mounted on the dog disc spindle 11 to rotate with the latter, which is in turn mounted for rotation on the hour hand spindle 2. Pivoted to the dog disc 70 12 is engaging the periphery of same as at 12 is a contact dog 13. A spring 14 has one end secured to the dog disc 10 and the opposite end connected to the contact dog 13.

It will be seen from the drawing that the 75 insulated annulus is scalloped on its inner periphery to receive therein the semi-circular contact members or segments 7, the flat edges of the latter being disposed at various angles with respect to one another. As the 80 contact dog 13 is rotated, it leaves one face at one contact and is adapted to snap into engagement with the face of the next succeeding segment 7. The positioning of these 85 segments so that they are at various angles enables a firm and positive contact to take place between the dog 13 and the face of said segments. This construction also relieves the spring 14 from time to time of its tension, thus saving the strength thereof. 90

A binding post 15 is connected to the dial of the clock for one wire of the electric circuit (not shown) while the second terminal of the time switch is designated by the numeral 16 which is connected to the circular 95 lever ring 4. A metal brace 17 connects the binding post 15 with the dog disc spindle 11.

In the installation and operation of my invention, the device as above described is placed on the hour spindle and over the dial 100 of the clock, and as shown in Fig. 1 the device is set to make and hold a contact for three hours from one o'clock until three o'clock, which is accomplished by moving the levers 9 into engagement with the metal 105 segments 7 which as above stated correspond to the hour marks on the dial of the clock. As the dog disc 10 rotates with the hour spindle 2, and when the contact dog 13 reaches the first metal segment which is connected with the circular metal ring through 110 one of the levers 9, an electric circuit is

closed, to the binding post 15, through the metal brush 17 to the disc spindle 11, then through the contact dog 13 to the metal segment, then through the connecting lever to the circular metal ring, then around the metal ring to the binding post 16. As shown the contact dog has passed the last metal segment which is connected with the metal ring to one of the connecting levers, the circuit is thus broken. In order to prevent any prolonged interruption in the electric circuit, the spring 14 instantly draws the contact dog 13 into contact with a new segment. For instance, in case the above device is used for heating a building, six of the connecting levers would be brought into engagement with the metal segments, so that a contact lasting an hour would be made every other hour as the hour hand of the clock revolves. While I have shown and described the preferred form of my invention, I realize that various minor changes may be resorted to, without departing from the spirit and scope of the invention as claimed, therefore, I do not wish to limit myself to the exact details of construction shown, nor the combination and arrangement of parts.

What I claim as new and desire to secure by Letters Patent is:

- 30 1. In a time switch, a rotary spindle, a disc mounted thereon, a metallic annulus arranged concentric with said spindle, an insulated annulus secured to the metal annulus, the inner periphery of said insulated annulus extending within the periphery of the first mentioned annulus, a plurality of metallic segments mounted on the inner periphery of said insulated annulus, a plurality of pivoted levers carried on said metallic annulus and adapted for contact respectively with the aforesaid segments, a pivoted dog

carried on said disc and having its free end in the path of said segments to contact with the latter as the disc is rotated, a coil spring having one end connected with the dog and its other end connected with said disc to normally urge said dog in a predetermined direction, and a connecting element engaged with said spindle and projecting radially therefrom to a point beyond the outer periphery of said metallic annulus, as and for the purposes described.

2. In a time switch, a rotary spindle, a disc carried thereon, a metallic annulus arranged concentric with said disc, an insulated annulus secured to the inner face of the metallic annulus and having its inner periphery projecting within the inner periphery of the first mentioned annulus, said inner periphery of the insulated annulus being scalloped, a plurality of metallic segments mounted in the scallops of said insulated annulus, a plurality of levers pivoted at their one ends to the outer face of said metallic annulus, the outer ends of said levers being adapted to be respectively moved into contact with the aforesaid segments at predetermined times, a pivoted contact dog carried on said disc, the free end of said dog being adapted for engagement with the respective segments as said disc is rotated, a coil spring having its one end engaged with said dog and its opposite end engaged with said disc to normally urge the dog in one direction, and a contact arm engaged at its one end with said spindle and projecting radially therefrom to a point beyond the outer periphery of said metallic annulus, as and for the purposes described.

In testimony whereof I affix my signature.

DELBERT HITCHCOCK.
